CONTAINER FOR SOAP DISPENSER

Howard G. Mullett and Robert J. Booker, Milwaukee,
Wis., assignors to Bradley Washfountain Co., Milwaukee, Wis., a corporation of Wisconsin

Filed May 10, 1963, Ser. No. 74,840

Term of patent 14 years

(Cl. D4—3)

Fig. 1

Fig. 2

FIG. 1 is a front view in elevation showing our design for a container for soap dispenser, and

FIG. 2 is a top plan view thereof.

The side opposite that shown in FIG. 1 is the same as that shown, and the bottom is flat and plain with the exception of the flanged opening as indicated by FIG. 1.

We claim:

The ornamental design for a container for soap dispenser, as shown and described.
